DESIGN FOR A COMBINED WASHER AND WRINGER DRIVE HOUSING

Merlin M. Jackson, San Jose, Calif.

Application April 10, 1944, Serial No. 113,198

Term of patent 14 years

(Cl. D49—1)

To all whom it may concern:

Be it known that I, Merlin M. Jackson, a citizen of the United States of America, and a resident of the city of San Jose, county of Santa Clara, and State of California, have invented a new, original, and ornamental Design for a Combined Washer and Wringer Drive Housing, of which the following is a specification, reference being had to the accompanying drawing, forming part of this application, in which:

Figure 1 is a top plan view of a combined washer and wringer drive housing, showing my new design;

Figure 2 is a side elevational view of the same; Figure 3 is an elevational view of one end thereof; and

Figure 4 is an elevational view of the other end of the same.

I claim:

The ornamental design for a combined washer and wringer drive housing, substantially as shown.

MERLIN M. JACKSON.
